UNITED STATES PATENT OFFICE.

JONATHAN T. BROWN, OF MARBLEHEAD, MASSACHUSETTS, ASSIGNOR TO
OLIVER A. MILLER, OF BROCKTON, MASSACHUSETTS.

DESIGN FOR A HINGE MEMBER FOR LASTS.

SPECIFICATION forming part of Design No. 34,731, dated July 2, 1901.

Application filed May 29, 1901. Serial No. 62,439. Term of patent 14 years.

To all whom it may concern:

Be it known that I, JONATHAN T. BROWN, of Marblehead, in the county of Essex and State of Massachusetts, have invented and 5 produced a new and original Design for Hinge Members for Lasts, of which the following is a specification.

This invention relates to a design for a hinge member for lasts.

10 The drawing is a perspective view showing my design.

The essential feature of my design consists in a web from one side of which project two parallel cylindrical lugs.

1 represents a web. 2 2 represent two lugs 15 projecting from one side of said web. The opposite side 3 of said web has a general crescent shape.

I claim—

The design for a hinge member for lasts, 20 substantially as shown and described.

In testimony whereof I have affixed my signature in presence of two witnesses.

JONATHAN T. BROWN.

Witnesses:

E. BATCHELDER,
H. L. ROBBINS.
